AUTOMATIC MACHINE GUN CHARGER

Thomas B. Slate, Washington, D. C., assignor to
 Slate Experimental Development Company,
 Burbank, Calif.

Application June 22, 1939, Serial No. 280,635

16 Claims. (Cl. 89—1)

The object of my invention is to provide a novel automatic machine gun charger for the Browning or other types of aircraft machine gun. My gun charger replaces the trigger solenoid and operates in place of the manual recharger. It is electrically controlled and can be installed in any electrical installation which has been wired for the present type trigger solenoid. Another object of my invention is to utilize carbon dioxide gas to furnish the power to charge the gun. It is also an object of the invention to lock the bolt of the gun in the rear position when the gun is not in use, leaving the barrel of the gun open at all times which aids in cooling the barrel and eliminates the possibility of a run-away gun. It is also an object of the invention to provide an automatic cut-off device which controls the main switch on the charger, to provide a positive manually controlled switch which will completely open the charging circuit after the charger has operated the gun consecutively for a predetermined number of times.

The art of machine gun recharging presents a problem in recharging the gun quick enough not to cause the operator to lose sight of his target or to have his attention distracted by the fact that the gun is not firing. Electrical rechargers are entirely too slow because of the time necessary for an electrical motor to build up speed and the item of its weight is a drawback when powerful enough to recharge quickly. Pressure cylinder rechargers, where the cylinder is stationary, operating a piston, has the problem of a packing gland on the piston to make it gas tight, having a variable amount of friction that changes when adjusting or tightening the piston gland; and there is also the problem of frosting when any part of the piston is exposed while the charger is in a stationary position.

One of the principal objects of my invention is to provide a recharger for machine guns that is extremely quick in action, and that requires the smallest fraction of time after the gun fails to fire before setting the recharger in action. In my invention such setting in action is entirely automatic and does not require the attention of the gun operator, and entirely replaces the usual trigger solenoid for setting the gun in action; it has its power cylinder piston mechanism completely covered by the cylinder when not in action; it has no stuffing glands on its piston to cause friction by tightness or to be affected by frost. It will automatically cease charging the gun after charging it a predeter-

mined number of times in succession without once firing, and will notify the operator by a pilot light if the charger is operating.

It is also my object to use liquid carbon dioxide gas as a source of carbon dioxide gas as it maintains high pressure and is anhydrous enough not to cause freezing of operating parts.

I attain these and other objects of my invention by the mechanism illustrated in the accompanying drawings, in which—

Fig. 43 is a side elevation of the cover plate 35.

Like characters of reference designate like parts in each of the several views.

Referring to the accompanying drawings, there is illustrated a conventional machine gun 1, having a forward mounting bracket 2 and a rear gun mounting bracket 3, as shown in Figs. 1 and 3, and a conventional manual recharging handle 4. The gun has a rear recharger guide block mounting slot 5 and a front recharger guide block and bolt head slot 5a. A rear recharger mounting guide block 6, as shown in Fig. 3, and the head of front recharger mounting guide bolt 6a seat in the slots 5 and 5a respectively, and bolt the charger to the gun.

The gun charger has a base plate 7, and cover 8, screws or bolts 9 holding the cover in place, firing control member 10, and a sear adjustment bolt 11 (shown in Figs. 2 and 10). As shown in Figs. 23, 24 and 25, member 7a is a hollow boss on base plate 7, through which the sear 10 extends to the sear adjustment bolt 11. Member 7b is an angle boss to receive gun locking arm 12 and its mounting pin which seats in aperture 12' but is not shown. Member 10 is a

sear used in the normal firing of the machine gun when the pin 61 is in the position shown in full lines in Fig. 3. Member 11 is shown best in Figs. 10 and 11. The sear adjustment bolt is usual equipment used on trigger solenoids.

A gun locking arm or sear 12 pivotally mounted at 12' (see Figs. 3, 29 and 9) engages core 44 at one end and has the other end projecting into the plane of the charging stud 61, which moves in slot 63 of the gun charger. Slot 63 is aligned with slot 62 of the gun to receive the charging stud 61 which oscillates in slots 62 and 63, as shown in Fig. 3. The spring 12a which bears against arm 12, as shown in Fig. 29, causes the latch 12 to catch pin 61, when solenoid 42 is deenergized, and locks the bolt of the gun to the rear when the charger is inoperative.

A spring-loaded pivoted cut out control arm 20 or lever 13 is provided as shown in Figs. 39, 9 and 42. Members 13' and 14' shown in Fig. 11, are openings for the protrusion of cut out control lever 13 and cut out 14. Lever 13 has a lug 13a, insulation block 13b and bend 13c, as shown in Fig. 39. As shown in Fig. 10, 13d is a spring normally holding lever 13 in contact with cam 15, and normally holding contact points 50 out of engagement. I provide an automatic cut out 14 (shown in Figs. 9, 41 and 37) which has a lug 14a and insulation block 14b. A novel automatic cylindrical cut out cam 15 has spaced ratchet elements 15' and cam elements A, B, C, and D—although any desired number, either more or less than four, can be provided, if desired. Forward of each of the cam surfaces A, B, C, D, is a ratchet surface 15', in a plane at right angles of that of cam 15 for engagement by pawl 20. 15a, shown in Figs. 35 and 36 is the opening in insulation block 34 and its cover 34' to receive the automatic cut out cam 15.

As shown in Figs. 9, 42 and 16, I provide an automatic cut out hollow arm 16 adapted to slidably receive the hollow cut out piston 17, in the longitudinal hollow portion 17b of which is mounted the piston spring 18, as shown in Fig. 42. Spring 18 tends to press the piston forwardly of the gun in the direction indicated by the dotted lines. The rear end of spring 18 is seated in a recessed portion of disk 16e, as shown, and presses against said disk, which is affixed to member 16. Piston 17 has an enlarged rear end 17a slidably in the enlarged annular recessed portion 16c of arm 16, as shown in Fig. 42. 16b designates the bore or channel in automatic cut out arm 16 to slidably receive piston 17. Spring 19 which is shorter and not as stiff as the spring 18 bears against the cover 8 at its rear end, and at its forward end against annular projection 16d of member 16 the automatic cut out arm 16 and tends to push it forwardly toward the mouth of the gun.

Referring to Figs. 9 and 42, spring 15e, which bears against and is mounted in the rear end of cam 15 is stiffer than spring 19, but not as stiff as spring 18 in piston 17. Spring 18 is sufficiently strong to compress spring 19 and spring 15e. Member 17 slides within member 16 and compresses spring 18 after member 16 has previously compressed spring 19 and abutted against the cover 8. When the annular projection 17a of member 17 engages the abutment 16g of member 16 at the end of recess 16c, members 16 and 17 move together as a unit. While the breech bolt is moving forwardly into battery, the pin 61 allows lug 13a of member 13

to flip up and catch a ratchet element of cam 13 before the sleeve is carried to the left by 17a. Pawl 20 pushes the ratchet the distance of one ratchet length to correspond essentially to the distance member 16 moves. The rest of the movement is absorbed by the compression of spring 18 and the movement of member 17 relative to member 16. This combination of spring action is such that when the charging cylinder 23 travels to the rear and pushes on piston 17, the first action is to move cut out arm 16 by compressing spring 18 to where pawl 20 will ride off of cut out pawl release pin 64 and engage ratchet 15' on part 15. Spring 18 in piston 17 will compress and then the very last part of the stroke of charging cylinder 23 moves cam 15 one notch. As the charging cylinder 23 and pin 61 return forward the spring pressure against piston 17 will continue to exert a force through pawl 20 against ratchets 15' of cam 15 until pin 61 slides off of cam 15c, whereby lug 13a of lever 13 will engage the ratchet face 15', of cam 15. Spring pressure on lever 13 tends to cause it to engage ratchet surfaces 15'. The pawl 20, as shown in Fig. 42 is pivotally suspended on pin or bolt 20a from the flanges 18a of automatic cut out arm 16 and is pressed downwardly by spring 21 to engage successively the cut out cam members B, C, and D.

Referring to Figs. 27 and 42, the bottom surface of pawl 20 is designated as 20b and is adapted to engage any of the ratchet surfaces 15' of cut out cam 15.

As shown in Figs. 9, 31 and 32, a charging cylinder extension or arm 22 is screw-threaded to charging cylinder 23 and has projections 22a and 22b. Projection 22b pulls 61 back. Projection 22a operates piston 17. Referring to Figs. 7 and 8, within charging cylinder 23 and encircling piston 24 is a return spring which causes the return of cylinder 23 when fluid pressure against same is relieved. Charging cylinder piston 24 has threaded ends 24d and 24b. As shown in Fig. 5, piston 24 has a longitudinal channel 24a extending through it from end to end. A gland 25, as shown in Figs. 7 and 8, is secured to the end of piston 24 by a suitable nut 26, said gland being slidable in cylinder 23, and functions to make the cylinder pressure tight.

As shown in Figs. 9, 13, 14 and 15, charging cylinder piston 24 is screw-threaded at its front end to valve body 27 and remains stationary while charging cylinder 23 is operated by the pressure of carbon dioxide flowing through a channel 24a of stationary piston 24. Charging cylinder extension 22, as shown in Figs. 32, 33 and 9, has an extension 22a which engages piston 17 and an extension 22b which engages charging pin 61. Piston channel 24a communicates with the valve port 31 in valve body 27. Mounted in valve chamber 29 of valve body 27 is a valve 28 having a needle point 30', as shown in detail in Fig. 34, and is preferably adjustable in length, as shown. Valve 28 is pressed by a spring 29a on the valve seat 30, as shown in Fig. 9. Opening out of valve chamber 29 is an exhaust port 29b, as shown in Fig. 13. Valve body 27 has a threaded recess 24c to receive the threaded end 24b of piston 24. Member 32, shown in Fig. 38, is a delay solenoid arm or flapper having contact point 33 and oppositely disposed spring 33a. Member 34, shown in Fig. 36 is an insulated block having a cover 34' (shown in Fig. 35). Member 34 has

an aperture 23' for the charging cylinder; an aperture 55' for solenoid 55; an aperture 34b for spring 33a; an aperture 34a for spring 12a; and an opening 16' for the automatic cut off arm 16; and opening 15a for the automatic cut out cam 15, as shown in Fig. 36.

Referring to Fig. 41, I provide a contact spring mechanism including automatic cut off switches or contact springs 36 and 37, said members having contact points 38.

Before any movement occurs on cam 15, lug 13a is engaging cam 15 at ratchet A. The first movement would move it to ratchet B, the second movement to ratchet C and the third movement to ratchet D. As shown in Fig. 41, the cylindrical rear end of cam 15 is of such length that it is equivalent of four positions of cam 15, allowing projection 14a to drop into cam A on the third movement. As shown in Fig. 41, lug 14a of cut out 14 is resting on the smooth surface of the cylindrical end of cam 15 in a position where it would take one or more movements to its fourth position to bring it to a position to allow lug 14a to drop into the first cam element and thereby separate contact points 38 of spring contacts 36 and 37. When cam 15 is pushed forward by pawl 20 until the spring tension of member 37 of automatic cut out lever 14 causes lug 14a to move into the first cam element, breaking contact elements 38, such operation thereby stops any further action of the charger. Lever 14, it will be noted, is pivotally mounted at 14c, as shown in Fig. 41.

Member 37 is a spring and is mounted in spring tension away from the contact point on member 36 and is held in contact against its tension by automatic cut out lever 14 through lug 14a in contact with the cut out cam 15. It is the cam 15 that holds the contact points 38 of contact springs 37 and 36 in contact.

As shown in Fig. 9, an electric conduit 39 carries the wires 51, 59 and 60. Also I provide a pressure pipe line 40 leading from a suitable source of pressure, preferably a container of liquid carbon dioxide (the container not being shown) to connection 40', which connects with passage 30 and thence to passage 31 through valve body 27.

As diagrammatically illustrated in Figs. 9 and 50 11, I provide a valve solenoid 41 and a gun lock solenoid 42, arranged in aligned position as shown. Valve solenoid 41 has a core 43; and gunlock solenoid 42 has a core 44. Electric current is supplied from a suitable source to valve 50 solenoid 41 by the valve solenoid wire 45; and to the gunlock solenoid 42 by the gunlock solenoid wire 46, as shown.

Referring to Fig. 10, I provide a valve solenoid spring 47 suitably secured in place, as by bolt 47a. I also provide a delay solenoid control spring 48 electrically connected with delay solenoid wire 52a. I also provide a delay solenoid contact spring 49 electrically connected with delay solenoid wire 52. Contact springs 48 and 49 carry contact points 50. I also provide a valve solenoid wire 45, shown in Fig. 40.

As shown in Figs. 9 and 11, the valve solenoid core 43 operatively engages valve control lever 54, which in turn operatively engages valve 28. As shown in Fig. 9, there is a delay solenoid or relay 55 having the usual core 56, as indicated diagrammatically in Fig. 40. As shown in Figs. 9 and 40, a wire 57 leads from switch 37 to the usual gun trigger (not shown). A wire 58 leads to a suitable source of electric supply such as a

battery. A wire 60 leads from switch 33 to pilot light 58.

As shown in Figs. 42 and 43, the stud 64 protrudes from the under side of cover plate 35 and engages pawl 20 when arm 18 is at rest in its front position (as shown in dotted lines), relative to the gun, and functions to disengage cut out pawl 20 from engagement with any of the four vertical or ratchet faces 15' of automatic cut out cam 15. This is to allow cam 15 to reset or return to its original position if the gun should fire normally and pin 61 engage the cut out control lever 13 and thereby disengage its lug 13a from the ratchet faces 15' of cam 15, allowing cam 15 to return to its original position. At the stage of operation illustrated in Fig. 42, lug 13a on lever 13 is out of contact with cut out cam 15 because pawl 20 is holding cam 15 in stationary rear position and will continue to do so as pin 61 contacts bend 13c of lever 13 and thereby operates lever 13.

The charging stud or pin 61 extends through and oscillates in slot 62 of the machine gun as shown in Fig. 3, and also extends through the corresponding slot 63 of the charger base plate 7. The function of pin 61 is to recharge the gun, either manually or automatically. My charger mechanism is bolted on the machine gun and held in place by guide blocks 6 and mounting bolts 6a, in slots 5 and 5a, respectively, of the machine gun. The heads of members 6 and 6a are beveled to engage the corresponding beveled walls of slots 5 and 5a of the machine gun to secure the charger to the gun.

To operate the charger, wire 57 is energized electrically by operating a trigger switch. Current flowing through main switch contact 38 to gun lock solenoid 42 causes the solenoid core 44 to push on gun locking arm 12, unlocking the gun, which allows it to start firing.

When the charging cylinder 23 pulls pin 61 to the rear, pin 61 rides upon the cam bend 13c of lever 13, which in turn closes contact points 50. Contact points 50 control the delay solenoid or relay 55, 56. When this circuit is closed by the operation of pin 61 riding over the bend 13c of lever 13 the delay relay 55, 56 is energized, whereupon it opens switch 32 and breaks the circuit and cuts off the flow of carbon dioxide gas, by reason of the broken circuit to the valve control solenoid. The delay solenoid or relay 55, 56 pulls on the small flapper 32 which opens switch 33.

When pin 61 returns forward off from cam 13 it opens switch 50, which in turn controls the delay relay. The delayed release of this relay 55, 56 after the circuit is broken is the action which controls the delay in the operation of the charger. When the holding power of the delay relay drops down to a point where the spring pressed flapper 32 closes switch 33, the charger functions again.

If the gun fires normally, charging stud 61 returns before the delay relay loses enough magnetic power to allow contact points 33 to close. Spring 13d (shown in Fig. 10) normally holds contact points 50 out of engagement and they are closed by the operation of cut out control arm 13, actuated by the operation of the charging pin 61.

When charging pin 61 leaves its locked open position it allows the lever 13 to open contact points 50 momentarily, if the gun fires normally, and allows them to remain open if it fails to fire. If the contact points remain open longer

than the normal time for charging pin 61 to return to its original or locked open position, delay solenoid 55, 56, releases the spring-actuated arm or flapper 32 allowing contact point 33 to close, and energizing valve solenoid 41 which pulls on core 43. Core 43 in turn operates lever 54, which actuates valve 28 to unseat it from valve seat and open passage 30 and simultaneously closes valve 29, allowing fluid pressure from pressure pipe line 40 to enter through passage 30 and port 31 into channel 24a of member 24 and flow into charging cylinder 23. This causes the charging cylinder 23 to move rearward, thereby pulling charging stud 61, by reason of its engagement by projection 22b, to its rear position.

It will be seen that when charging pin 61 contacts cut out control lever 13 at cam bend 13c it causes contact points 50 to close reenergizing delay relay 55, 56, and consequently opens contact points 33, thereby deenergizing valve solenoid 41, and allowing pressure valve 30 (Fig. 9) to close and exhaust valve 29 to open, allowing cylinder 23 to return to its original position due to the action of spring 23a (Fig. 7), thus causing the gun to resume firing.

When charging cylinder 23 operates, in the process of recharging, its cylinder arm projection 22a contacts piston 17 and operates arm 16 and pawl 20, which is carried by arm 16, and pushes piston 17 to its extreme rear position. When arm 16 returns by the action of spring 18 to its original position, pawl 20 rests on stud 64, which holds it out of contact with cam 15, as indicated by dotted lines in Fig. 42.

If the gun fires after recharging after the first time, pin 61 pushes arm 13 and its lug 13a out of contact with cam B, allowing cam 15, pressed by spring 15a to return to its original forward position. If the gun fails to fire when recharged, lug 13a retains contact with cam 15, while pawl 20 moves to cam C. Consequently if the gun continues to fail to fire pawl 20 moves from cam B to cam C, and D, consecutively, lug 13a of lever 13 retaining cam 15 in its consecutive positions. In the final position, lock lug 14a (Fig. 41) engages the ratchet surface 15' adjacent cam A of cam 15, opening main switch contact points 38 and stopping the charger from further recharging. If, however, the gun fires before cam D is reached, cam 15 is returned to its original position and will again permit the gun to recharge one, two, or three times, as before, if it should again fail to fire.

When the operator holds the trigger switch in contact and the gun fails to fire normally, contact points 33 close, thereby electrically connecting valve solenoid 41 and pilot light 58 through wire 60, causing the pilot light to glow each time the charger recharges the gun. If the gun fails to fire after three consecutive rechargings, and contact points 33 are opened, the pilot light 58 will cease to glow, indicating that the automatic cut out has functioned as provided for.

To recharge the gun after recharger cut out has functioned, press levers 13 and 14 down simultaneously. This disengages lugs 13a and 14a from cam 15 and resets the charger for continued operation.

What I claim is:

1. In a new article of manufacture for use in an automatic machine gun charger, a hollow cut out arm comprising a hollow cylindrical element having a circumferentially enlarged portion, a

spring bearing against said portion urging said arm in one direction, said arm having a portion of its interior circumferentially enlarged to form an annular chamber, a hollow piston slidably mounted in said arm, a spring contained within said piston and tending to move it in the same direction as said arm and relative to it to the limit of its movement, said piston having a circumferentially enlarged inner end slidable in the annular chamber of the aforesaid arm, a spring-pressed pawl carried by the aforesaid arm, said pawl having a front and bottom operative surface, a cam adapted to be engaged by said pawl including a series of frusto-conical cam faces spaced from each other and connected by a cylindrical element, and a series of pawl-contacting surfaces disposed in a plane at right angles to that of the cylindrical element, one surface intersecting each cam face so that the pawl-contacting surfaces are spaced parallel to and equidistant from each other.

2. In an automatic gun charger, the combination of electrically-controlled means for recharging the gun, an electric circuit attached to and controlling said means, a normally closed automatic cut-out switch in said circuit, a cut-out control member operatively connected to said switch, a charging element, fluid pressure means for actuating said charger element and operatively connected to same, said control member including a cam having spaced frusto-conical cam faces, and a series of ratchet surfaces disposed in a plane at an angle to the aforesaid cam faces, a pawl adapted to operate said cam and to be operated by said charging element the control member including a cylindrical end member of the same length as the total length of the aforesaid cam and ratchet members, said cylindrical end member being adapted to release the automatic cut out switch to a position to open the circuit after a predetermined number of successive recharges, and means to automatically reset said cam if the gun functions normally before said predetermined number of recharges.

3. In combination with the mechanism defined in claim 2, a manually controlled means in the circuit arranged to close the charger circuit after the charger has operated the gun successively for a predetermined number of successive recharges.

4. In an automatic gun charger, the combination of electrically-controlled means for recharging the gun, including a charging element, and fluid pressure means operatively connected to said element for actuating same, an electric circuit connected to and controlling said means, a normally closed switch in said circuit, an automatic cut out switch control lever having a projecting lug, a cam including a series of frusto-conical cam faces spaced from each other and connected by a connecting element, a series of pawl contacting surfaces on said cam disposed in a plane at right angles to that of the connecting element and spaced equal distances apart, a pawl engaging said cams and operated by said charging element, said cam including a cylindrical section forming a continuation of the element and of the same length as the total length of the series of cam and ratchet elements and supporting the lug of the automatic cut out switch control lever in position to hold the switch in closed circuit for a predetermined number of successive recharges.

5. In combination with the mechanism defined in claim 4, said fluid pressure means including a valve means for admission of fluid under pres-

sure for actuating said charging element, said valve means having a single combined needle and poppet valve element acting as intake and exhaust valve, and a single lever attached thereto and operating same.

6. For an automatic gun having a reciprocating breech bolt, a charger comprising a source of fluid under pressure, a pressure actuated element adapted to charge the gun, a valve connected between the said source of fluid and said pressure actuated element for admission of fluid under pressure for actuating said charging element, a first electric circuit including a source of current and means for operating said valve, means for locking the bolt of the gun in rear position, spring means urging said locking means to operative position, a second circuit including said source of current and means for moving said locking means to inoperative position, a third circuit including said source of current and means for controlling a predetermined number of successive recharges of the gun, a normally closed switch common to said first, second and third circuits and including spring contact members, an automatic cut-out device for controlling the aforesaid switch and comprising a spring pressed pivoted member for operating one of said spring contact members to open said switch, said pivoted member having a projecting lug, the aforesaid cut-out device including a cam constructed and arranged to be actuated by said charging element and comprising a plurality of linearly spaced conical cam elements and a cylindrical section in contact with said lug to hold said pivoted member out of operative position, said cylindrical section being of a predetermined length corresponding with the overall length of the cam elements and constructed so that movement of said cam allows said pivoted member to come into switch opening position.
7. In an automatic gun charge, an automatic cut out device comprising a ratchet like cam having a series of conical cam faces, a series of pawl contacting faces, said faces being linearly spaced equal distances apart, a cylindrical element forming a continuation of the cam member and being of the same length as the total length of the series of cam and ratchet faces, and an electric circuit including an automatic cut out switch in contact with said cylindrical member and adapted to be held in position to close the circuit for a predetermined number of successive recharges, a pawl adapted to engage any of said ratchet faces, a spring controlled element carrying said pawl, and a pivotally mounted switch control arm having a lug in contact with a pawl-contacting face and adapted to be moved by said cam faces into engagement with a succeeding one of the aforesaid pawl contacting faces and disposed in a position to be brought into or out of position with said cam faces.
8. For a machine gun having a reciprocating charging pin, a charger mechanism adapted to be fastened to the machine gun and including a slidably pressure controlled charging cylinder operably engageable with the charging pin, a cut out arm, a spring actuating said cut out arm, a piston mounted in the path of said charging cylinder, having a slidable movement in said arm, a spring actuating said piston and arm to move same forwardly of the gun, a spring pressed pawl carried by the aforesaid cut out arm, an automatic cut out cam having spaced cam and ratchet element with which said pawl is operably engageable, a pivoted cut out control lever in lock-

ing engagement with the aforesaid spaced ratchet element of the said cut out cam, said lever having an element thereof engageable by the charging pin of the gun to release said lever from operative engagement with the said cut out cam at predetermined times.

9. In combination with a machine gun having a charging pin, the charger mechanism adapted to be fastened to a machine gun and comprising a gun locking device, electrical mechanism for operating said device to unlock the gun, a slideable pressure controlled charging cylinder operably engageable with the charging pin, a spring pressure operated hollow cut out arm, a spring pressure operated hollow piston having a limited slideable movement in said hollow arm mounted in the path of said charging cylinder, and a spring operatively connected to and tending to move the piston and arm forwardly of the gun, said piston being actuated by the charging cylinder, a spring-pressed pawl carried by the aforesaid hollow cut out arm, an automatic cut out cam having spaced cam and ratchet elements with which said pawl is operably engageable, a pivoted cut out control lever in locking engagement with any of the aforesaid ratchet elements, said cut out control lever having an element thereof engageable by the charging pin of the gun to release said lever from operative engagement with the cut out cam at predetermined times, and a fixed stud disposed in the path of the aforesaid pawl to disengage same from operative connection with the automatic cut out cam.

10. In combination with a gun having a reciprocating charging pin, a charging mechanism adapted to be fastened to the machine gun and including a control means for said charger mechanism, a lever element for actuating said control means to inoperative position, a locking device mounted on said charging mechanism to unlock the charging pin, electrical means for operating said locking device to unlock the charging pin, an automatic cam mounted on said gun, said cam having spaced cam and ratchet elements and a cylindrical element engageable by said lever element to hold it in inoperative position, a pivoted cut out control lever operably engageable with any of said spaced ratchet elements of said cam to lock the cam, said lever having a portion thereof also engageable with the charging pin to disengage said lever from the automatic cut out cam at predetermined times when the charging pin is operated.

11. In combination with the mechanism defined in claim 10, a valve controlled fluid pressure supply means said charger mechanism also including a stationary hollow piston in communication with said valve-controlled fluid pressure supply means, a charging cylinder slidably mounted on said piston, a spring tending to return said charging cylinder to its original forward position, a hollow cut out arm, a light spring actuating said arm, a hollow piston slidably mounted in said cut out arm, a heavier spring mounted in said piston, the said piston and the said arm having means for operative engagement after a limited movement of the piston in the arm to cause them to move as a unit in one direction, the aforesaid piston being operably engageable by an element of the charging cylinder, a pawl carried by the aforesaid cut out arm, said pawl being engageable with any of the ratchet elements of the cut out cam, a stud mounted on the charger mechanism and protruding in the path of said pawl to disengage it from the ratchet

element, and a spring engaging the cut out cam and tending to actuate it to its forward position.

12. In combination with a machine gun having a charging pin, a charger mechanism adapted to be attached to the machine gun, said mechanism including a charging cylinder, a hollow cylindrical cut out arm arranged to be actuated by the charging cylinder, said hollow cut out arm having an annularly enlarged interior portion, a hollow piston slidably mounted in said arm, said piston having an enlarged head slidable in the aforesaid enlarged interior portion of the arm, a short spring pressing against the cut out arm to press it forwardly, a longer spring mounted in and pressing against the piston to press it forwardly, a spring-pressed pawl carried by the aforesaid cut out arm, a cut out cam having spaced ratchet and cam elements, each being engageable by the aforesaid pawl under predetermined conditions, a cover plate of the charger having a stud positioned to disengage the pawl from said cut out cam, a pivoted cut out control lever shaped to be engaged and operated by the charging pin, said lever having an element adapted to operatively engage any of the spaced ratchet elements of the cam to lock same.

13. In combination with the mechanism defined in claim 12, the aforesaid cam elements comprising frusto-conical cam faces connected by a cylindrical element, each of the cam elements terminating in a ratchet element, said ratchet elements being spaced equal distances apart for engagement by the aforesaid pawl.

14. In combination with a machine gun having a charging pin, a charger mechanism adapted to be fastened to the machine gun and including a charging cylinder, valve-controlled means for supplying fluid under pressure to and thereby actuating the charging cylinder, spring means for returning the charging cylinder to its original position, electrically controlled means for locking the bolt of the gun in rear position when the gun is not in use, a hollow cut out arm having a spring pressing it forwardly of the gun, a hollow cut out piston mounted in said arm and having a longer spring of different tension from the first-mentioned spring pressing the piston forwardly, said piston being operable by the charging cylinder, said cut out arm carrying a spring-pressed pawl, a cut out cam having a series of spaced cam and ratchet elements with which the aforesaid pawl is releasably engageable, a spring pressing said cam forwardly, an automatic cut out switch mounted on said charger, the aforesaid cam having a cylindrical element engageable by the automatic cut out switch to hold said switch in closed position for a predetermined number of successive recharges corresponding with the number of cut out ratchets on the cam, said cylindrical element being of the same length as the total length of the spaced cam and ratchet elements.

15. In combination with a machine gun having a charger pin, a gun charging mechanism adapted to engage said pin and including a charging cylinder engaging the charging pin, valve controlled means for actuating the cylinder by fluid pressure, spring means to return the charging cylinder to original position, means for locking the bolt of the gun in rear position when the gun is not in use, a cut out arm and spring-pressed cut out piston actuated by the charging cylinder, said cut out arm having a pawl, a cut out cam engageable by said pawl, said pawl in turn being releasable from the cut out cam by the operation

of the charging pin, the automatic cut out device controlling the main switch on the charger, and including spring contact members, a pivoted member having a projecting lug, said pivoted member being in operative contact with one of the spring contact members, the aforesaid cut out cam having a series of ratchets, and having a cylindrical section of a length corresponding with the length of the aforesaid cam and ratchet elements and adapted to hold the switch in open position a predetermined time while the lug of the pivoted member of the automatic cut out device is in operative contact with said cylindrical end of the cam to limit the operation of the charging mechanism to the number of ratchets used.

16. In combination with a machine gun having

a charging pin, a charger mechanism adapted to be attached to the machine gun, a charging cylinder, fluid operated means for actuating the charging cylinder, electrical means for locking of the gun for a predetermined period of time, a spring-pressed cut out arm and piston mechanism actuated by the charging cylinder, a cut out cam actuated by said cut out arm and piston mechanism for controlling the recharging of the gun a predetermined number of times, trigger switch operated electrical means for setting the gun in operation, and an automatic cut out switch controlled by the cut out cam to open the circuit after the gun has been recharged the predetermined number of times.

THOMAS B. SLATE.
